UNITED STATES PATENT OFFICE.

FRANK E. WILSON, OF LANCASTER, OHIO.

GAME-BOARD.

1,106,530.

Specification of Letters Patent. Patented Aug. 11, 1914.

Application filed February 25, 1913. Serial No. 750,684.

To all whom it may concern:

Be it known that I, FRANK E. WILSON, citizen of the United States, residing at Lancaster, in the county of Fairfield and 5 State of Ohio, have invented certain new and useful Improvements in Game-Boards, of which the following is a specification.

This invention relates to game boards, and more particularly to a game board designed 10 for use in playing a game simulating the ordinary game of baseball, and it is one aim of the invention to provide such a board so constructed that every possible play of the ordinary game may be indicated on the 15 board when played upon.

A further aim of the invention is to provide a board of the type mentioned with means for separately recording the batting, fielding, and base-running results in detail, 20 as accurately as indicated by the different plays of the different players in the course of the ordinary game. In this connection the invention aims to provide means for holding the projectile; employed in connection 25 with the board, at the completion of every play until the result has been observed and recorded.

For a full understanding of the invention reference is to be had to the following description and accompanying drawing, in 30 which:—

Figure 1 is a top plan view of the game board embodying the present invention. Fig. 2 is a vertical longitudinal sectional 35 view therethrough. Fig. 3 is a vertical transverse sectional view.

Corresponding and like parts are referred to in the following description and indicated in all the views of the accompanying drawing 40 by the same reference characters.

The board includes a runway composed of a baseboard 1 having sides 2 which extend throughout its entire length, this board being supported in inclined position by 45 means of a cleat 3 secured transversely upon its under side at its end opposite the end at which the players stand.

A board 4 is supported at its lateral edges between the sides 2 and lies in spaced relation 50 to the board 1, above the same, and in a plane parallel to the plane occupied by the said board 1, and this board 4 extends from the elevated end of the board, as a whole, to a point near that end of the board at 55 which the players stand, as shown in Figs. 1 and 2 of the drawing.

For a purpose to be presently explained, pins or pegs 5 are secured in the board 4 and project upwardly from the same, and these pins are arranged in transversely extending 60 series and in staggered relation, as shown in Fig. 1. There is also secured upon the upper side of the board 4 at the rear edge thereof, a strip 6 in the forward side of which are formed a number of notches 6' 65 constituting pockets in which the projectile used in connection with the board may lodge, as will hereinafter be explained.

A pocket plate 8 is normally supported flat upon the forward portion of the board 4 and the means for supporting this plate is embodied in rockers, each formed from a suitable length of wire 9 bent at its ends at right angles, as at 10, and thence outwardly at right angles, as at 11, the said ends 11 being pivotally fitted in openings in the sides 2 of the board. As stated, the plate 8 normally rests flat upon the upper surface of the board 4 and when in this position the rockers assume the dotted line position 80 shown in Fig. 2. A handle 12 is provided at the rear edge of the plate 8 and may be grasped for the purpose of swinging this plate upwardly in the direction of that end of the board at which the players stand until 85 it assumes about the position shown in dotted lines in the said Fig. 2. The purpose of so mounting this plate and the reason for swinging it to assume the dotted line position will be presently fully set forth. The 90 plate 8 is formed near its end with three series of openings, one indicated by the numeral 13, another by the numeral 14 and the third by the numeral 15. These series preferably extend in parallelism, and the series 13 is located in advance of the series 14 and the series 15 is located in rear of the series 14. The openings of the series 13 are 95 preferably indicated by a legend, such for example as "Foul balls," the openings of the series 14 by a legend, such for example as "Balls," and those of the series 15 by a legend, such as "Strikes." An opening 16 is formed in the plate 8 in rear of the series of the openings 15 and indicates the catcher's 100 position, and for this reason is indicated by the legend "Catcher." The opening 16 is preferably of greater diameter than the openings of either series 13, 14 and 15 and formed in the plate at each side of the opening 16 is a smaller opening 17. The reasons 105 for providing these openings 17 will be 110

made clear in the description of the use of the board.

A transversely extending series of openings 18 is formed in the plate 8 rearwardly of the openings 16 and 17, and the openings of the series 18 are indicated by letters or combinations of letters signifying "Bunt," "Single," "Bunt safe." The opening 16 is located at the longitudinal median line of the plate 8, as will be observed from inspection of Fig. 1, and the openings 17 are but slightly spaced therefrom, and it will be observed that the series of openings 18 extends entirely across the said plate, and that these openings are positioned relatively close to each other. Openings 19, 20, and 21 are formed in the plate 8 in transverse alignment, the opening 19 indicating the pitcher's position and the openings 20 and 21 indicating, respectively, the location of first and third bases, the opening 19 being located in front to rear alignment with the opening 16 and the openings 20 and 21 being located one at each side of the opening 19. The plate 8 is formed with three openings 22, one located at each side of the opening 20 and one rearwardly thereof, other openings 23 being similarly located with respect to the opening 19, and other openings 24 being located in like relation to the opening 21. The short stop position is indicated by an opening 25 formed in the plate rearwardly of and between the openings 19 and 21, and openings 26 and 27 are formed in the plate adjacent to the opening 25. Second base position is indicated by an opening 28 adjacent to which are located openings 29 having the same relation to the opening 28 as the openings 22 to the opening 20. The opening 29 is located in a transversely extending series of openings 30, this series extending entirely across the plate in rear of the opening 28. The openings of the series 30 are indicated from each side toward the center by numerals and letters signifying "Single," "Two base hit," "Three base hit" and "Home run." Center field position is indicated by an opening 31 and right and left field positions are indicated respectively, by openings 32 and 33. Openings 34, 35 and 36 are formed in the plate 8 and bear the same relation to the openings 29, 31 and 33, respectively, as do the openings 22 to the opening 20, etc. Openings 34^a, 35^a and 36^a are formed in the plate rearwardly of the openings 32, 35 and 33, respectively, and are indicated respectively by characters signifying "Three base hit," "Home run" and "Three base hit." A strip 37 is secured transversely upon the upper side of the plate 8 at the rear end edge thereof and is formed in its forward edge with a number of notches 38, and the plate 8 is formed within the curvature of the wall of each notch with an opening 39.

There are nine of the openings 39 and upon the strip 37 adjacent each opening 39 there is a legend, such for example as "Ball," "Called strike," these legends or indications being preferably alternated throughout the series. Three rows of pins 39' are arranged upon the upper face of the plate 8 in the same manner as are the pins 5 upon the floor 4, and these pins are located between the openings 34^a, 35^a and 36^a and the said strip 37.

A device to be presently described is provided for propelling a projectile over the upper surface of the board 1 in the direction of the forward end thereof, and as a means for directing this projectile, which is indicated by the numeral 40, and is in the nature of a marble or small ball, onto the pocket plate 8 there is provided at the forward end of the board 1, a deflecting device comprising a plate 41 which is secured at one edge to the said forward end of the board 1, and is curved upwardly and thence forwardly with its other edge terminating above the forward end of the pocket plate 8. This plate 41 extends entirely across the board as a whole and its curvature from its lower to its upper edge is paraboliform. The deflector plate is curved as stated, so that the projectile 40 is liable to leave or deviate from the course defined by the plate at any one of a number of points, depending upon the force with which it is propelled over the surface of the board 1. In this manner the point at which the projectile will land upon the pocket plate is rendered problematical although it may be determined with more or less accuracy by a skilled player.

The device for propelling the projectile over the board 1 comprises a resilient arm 42 which at one end is confined between posts or pins 43 and 44, the post 43 being located nearer the left-hand side board 2 than the post 44 and bearing against the forward side, whereas the post 44 bears against the rear side. A stop-pin 45 is fixed in the board 1 and serves to limit the forward movement of the arm 42. The free end of the arm is enlarged to form a head 46 having a concave forward side 47 in which the projectile 40 is lodged prior to being driven over the board, and this head terminates in a finger-piece 48 which may be grasped for the purpose of springing the arm rearwardly against its tension, the arm being released after being so sprung, and upon being released being designed to forcibly roll the projectile 40 forwardly and upwardly along the upper surface of the board 1 and with greater or less force against the deflector 41.

The board 1 has marked upon its upper face rearwardly of the floor 4, a diamond and a number of squares within which may

be disposed disks 50 representing the different players, the word "Out" being printed in the space to the left of the diamond and the word "Score" being located 5 in the space to the right of the diamond.

By referring to Fig. 2 of the drawing, it will be observed that the board 4 serves as a bottom for each of the pockets formed by the openings in the pocket-plate 8 and that 10 when the projectile 40 has lodged in any one of these openings it will remain therein so long as the pocket-plate 8 is in full line position shown in said figure. However, when the pocket-plate has been swung upwardly and rearwardly to assume about the dotted line position the projectile will be 15 released and will roll down the board 4.

The player, of course, represents the batter and he manipulates the projectile propelling devices so as to more or less forcibly roll the projectile along the upper surface of the board 1 and against the concave surface of the deflector 41. After the ball leaves the deflector it falls onto the pocket 25 plate 8 and will eventually lodge in one of the openings formed in this plate. After the score, indicated by the projectile lodging in one or another of the openings, has been noted, the handle 12 is grasped and the plate 30 is swung rearwardly and upwardly so as to release the projectile and allow it to roll down the board and into one of the pockets 7, it passing first between the pins 5 upon the said board 4.

35 The scores or plays indicated by the different openings has before been stated, and is clearly indicated in Fig. 1 of the drawing, and it will be understood therefore that if the projectile or ball falls into one of the 40 openings 13 it is a "foul", or if it lodges in any of the openings 14 the batter is credited with a "ball." If the projectile lodges in any one of the openings 15, a "strike" is registered against the batter. On the 45 other hand, if the ball lodges in the opening 20, for example, it indicates that the batter is out on a "fly" to the first baseman. Should it lodge in any one of the openings 22, it indicates that the batter is out on an 50 "assist" by the first baseman. If the projectile lodges in any one of the openings 30, for example, the ones indicated by the legend "Single" it indicates that the batter is safe on a "single," but if it lands in one 55 of the openings 18 indicated by the legend "Bunt" he may either be "safe", "out" or "score", depending upon which one of the pockets 7 the projectile enters after the pocket-plate has been swung up.

60 In the event that the projectile passes all of the openings in the packet-plate 8 and lodges in one of the openings 39 within the pockets 38 it indicates that the batter has hit the ball and some one has made an error 65 in fielding it. Before lodging in any one

of these openings, however, the projectile must pass between two or more series of pins 39 arranged in staggered relation in front of said openings. The question to be then determined is what becomes of the batter. 70 For this purpose the plate 8 is swung up and the ball is allowed to roll down the plate 4 and into one of the pockets 7, thus indicating whether the batter is "out", "safe", or "scores". If there should be a runner 75 on any of the bases when an error is made the ball must be allowed to roll down the board 4 to determine whether he is "out", "safe", or "scores" and then the ball must be replaced in the same pocket and again 80 allowed to roll down the board 4 to see whether the batter who caused the error is "out", "safe", or "scores".

It will be apparent that the players can 85 keep track of the various plays made and the positions of the base runners by placing the disks 50 at the proper points upon the diamond and, when a base runner is "out" or "scores", in the space to the left or right of the diamond. 90

Having thus described my invention, what is claimed is:

1. A game board having superposed surfaces arranged for the successive movement of a projectile thereover, means arranged upon one of the surfaces for coöperation with the projectile to retain the same in position to indicate a score, and means for releasing the projectile for movement over the other surface, the last-mentioned surface 100 having means thereon for indicating a phase of the score not indicated upon the first-mentioned surface. 95

2. A game board having superposed members arranged for the movement of a projectile thereover, the upper one of the members having a score-indicating pocket to receive the projectile, and the other member having a score-indicating means thereon, one of the members being displaceable with 110 relation to the other member whereby to release the projectile for movement upon the second-mentioned member. 105

3. A game board having superposed relatively displaceable members, one of the members having a pocket to receive a projectile, and the other member forming a bottom for the pocket except when the members are displaced, and score-indicating means upon each of the members. 115

4. A game board including relatively displaceable members arranged for the movement of a projectile thereover, one of the said members being formed with an indicated pocket, and the other member normally forming a bottom for the pocket, the pocket being arranged to receive a projectile and retain the same when the members are in normal position and to discharge the projectile when the members are relatively 125 130

- displaced, and score-indicating means upon the second-mentioned member.
5. A game board, having superposed surfaces arranged for the movement of a projectile thereover, the surfaces having thereon independent score-indicating means, means upon one of the surfaces for retaining a projectile in indicating position thereon, and means whereby one of the surfaces may 10 be displaced with relation to the other to release the projectile.
6. A game board having a surface arranged for the movement thereover of a projectile, the said surface having thereon a 15 score-indicating means, a pocket plate arranged above the said surface and having an indicated pocket arranged to receive the projectile, the said surface forming a bottom for the pocket when the plate is in normal position, and means whereby the plate 20 may be displaced with relation to the said surface to release the projectile lodged in said pocket.
7. A game board having a surface arranged for the movement of a projectile 25
- thereover and having thereon a score-indicating means, and a member supported for upward displacement with relation to the surface and having an indicated pocket, said surface forming a bottom for the pocket 30 when the member is in normal position.
8. In a device of the class described, a member arranged for the movement thereover of a projectile, a plate arranged to normally rest upon the board and having 35 pockets formed thereon, the said board constituting the bottoms of the pockets, the pockets being indicated and being arranged to receive the projectile, the said board having thereon score-indicating means, and 40 means whereby the said plate may be bodily displaced with relation to the board whereby to discharge the projectile from the pocket therein in which it has lodged.

In testimony whereof, I affix my signature 45
in presence of two witnesses.
